UNITED STATES PATENT OFFICE.

ANTONIO BONGIOVANNI, OF BARNESBORO, PENNSYLVANIA.

HOLDER OR CASTER FOR CONDIMENT-RECEPTACLES.

1,215,333.

Specification of Letters Patent.

Patented Feb. 13, 1917.

Application filed August 2, 1916. Serial No. 112,754.

To all whom it may concern:

Be it known that I, ANTONIO BONGIOVANNI, a citizen of the United States, residing at Barnesboro, in the county of Cambria, State of Pennsylvania, have invented a new and useful Holder or Caster for Condiment-Receptacles; and I do hereby declare the following to be a full, clear, and exact description of the invention, such as will enable others skilled in the art to which it appertains to make and use the same.

This invention relates to an improved holder or caster for condiment containers and the like, and an object of the invention is to provide a vertical support, to be supported upon a counter or table, and having a combined extensible and rotating frame mounted thereon, to support the condiment containers, in such a manner that persons at diametrically opposite positions of the table, may extend the frame, remove the desired container, then use it and return it to the frame, and subsequently collapse the frame. A further object of the invention is to provide a detent ratchet for the revolving frame.

A further object of the invention is the provision of an improved holder for each container.

In practical fields the details of construction may necessitate alterations falling within the scope of what is claimed.

The invention comprises further features and combination of parts as hereinafter set forth, shown in the drawings and claimed.

In the drawings:—

Figure 1 is a view in perspective of the improved caster or holder constructed in accordance with the invention.

Fig. 2 is a plan view, showing the frame of the caster or holder extended.

Fig. 3 is a sectional view on line 3—3 of Fig. 2.

Fig. 4 is an enlarged detail transverse sectional view on line 4—4 of Fig. 3, showing the detent ratchet means.

Referring more especially to the drawings 1 designates a base, which may be secured by screws or the like to a counter or table 2, preferably such as those used in lunch rooms and other public eating places. Rising from the base 1 is a standard 3, the upper greater portion of which is hollowed out cylindrically, and which hollow is designated by the numeral 4. The bottom of the hollow 4 is provided with a tapered lug

5. Telescoping into the hollow 4 is a cylindrical post 6, the lower end of which is provided with a tapered upwardly extending depression 7, which engages upon the upper extremity of the lug 5, thereby affording a thrust bearing for the post 6. The cylindrical post 6 is provided with a series of annularly arranged ratchet teeth 8. The wall of the hollow part of the standard 3 is provided with an opening 9, which receives the detent pin 10, the conical extremity 11 of which is designed to ratchet over the teeth 8, when the post 6 is rotated in one direction or the other. This detent pin 10 is so connected at 12 to the detent lever 13 (which is pivoted at 14 between the two ears 15,) so that by depressing the end 16 of the lever, the pin 10 may be withdrawn from engagement with said teeth 8, that post 6 may be removed or may be freely rotated without the pin ratcheting over the teeth. The lever 13 is under tension of the spring 17, which is seated in the recess 18 of the exterior of the standard 3, so as to normally hold the conical end of the pin 10 in engagement with the teeth 8. The upper part of the post 6 has a rectangular portion 19, and extending from this portion axially is a reduced cylindrical part 20. The rectangular portion 19 fits a corresponding rectangular recess 21 in the lower face of the lazy-tong bar 22, so that the bar 22 will move with the post 6. The cylindrical reduced extension 20 extends through the bar 22, and also through the lazy-tong bar 23, so that the bar 23 will pivot upon the extension 20. The upper end of the extension 20 is riveted, to provide the head 24, to prevent disconnection of the bars 22 and 23. The end portions 25, 26, 27 and 28 of the bars 22 and 23 are pivoted to the lazy-tong bars 30 and 31, by means of the pivot pins 32, which are riveted at 33. The adjacent ends of the bars 30 are pivoted together by the pin 34, and the bars 31 are pivoted together by the pin 35, which pins 34 and 35 are riveted as shown at 36 to prevent disconnection of the parts. The pivot pins 32, 34, and 35 are carried by downwardly extending handles 37, which may be grasped by the hand of a person at the table or counter, whereby the frame (which is constructed of the lazy-tong bars) may be extended. Secured to the bars 30 and 31 by means of suitable screws 38 are plates 39 integral with which the rings 40 are constructed. These rings 40

are designed to receive condiment containers there being arms 41 constructed integral with the rings, to prevent the containers from slipping through the rings. By grasping either one of the handles the frame may be extended, whereby a container may be easily removed.

The invention having been set forth what is claimed as new and useful is:—

10 In a caster, the combination of an extensible frame consisting of a plurality of lazy-tong bars and a standard comprising two sections, one of which being fixed to one of the lazy-tong bars of the frame and pivoted 15 to an adjacent bar thereof, of detent ratchet

means between the two sections, whereby one section may be held adjustably revoluble in the other section, said frame having condiment container holders, and handles carried by the pivots of the lazy-tong bars, for extending and collapsing the frame. 20

In testimony whereof I have signed my name to this specification in the presence of two subscribing witnesses.

ANTONIO BONGIOVANNI.
